(57) **ABSTRACT**

There is provided an elevator control system capable of improving operation efficiency of an elevator. The elevator control system includes a processor; and a memory to store a program which performs processes of recognizing a floor based on information from in a car of an elevator during travel of the car, determining a destination floor based on the floor recognized, determining whether or not the destination floor determined during the travel of the car, and registering a call corresponding to the destination floor in the car during the travel of the car in a case where the destination floor is determined to be the stoppable floor. The program performs processes of, in a case where the destination floor is not determined to be the stoppable floor, registering the call corresponding to the destination floor in the car after the car responds to all calls registered in the car.

1
ELEVATOR CONTROL SYSTEM

FIELD

The invention relates to an elevator control system.

BACKGROUND

PTL 1 discloses an elevator control system. The control system disables voice recognition during travel of a car. Accordingly, it is possible to prevent erroneous recognition caused by noise of a moving car.

CITATION LIST

Patent Literature

[PTL 1] Japanese Patent Application Laid-open No. 2013-52957

SUMMARY

Technical Problem

However, in the control system, it is not possible to register a call by the voice recognition during the travel of the car. As a result, operation efficiency of an elevator is reduced.

The invention has been made in order to solve the above problem. An object of the invention is to provide an elevator control system capable of improving the operation efficiency of the elevator.

Solution to Problem

An elevator control system according to the invention includes a voice input section provided in a car of an elevator, the voice input section receiving an input of a voice uttered in the car during travel of the car, a voice recognition section configured to recognize a floor based on the voice input to the voice input section, a destination floor determination section configured to determine a destination floor based on the floor recognized by the voice recognition section, a stoppable floor determination section configured to determine whether or not the destination floor determined by the destination floor determination section is a stoppable floor during the travel of the car, and a call registration section configured to register a call corresponding to the destination floor in the car during the travel of the car in a case where the destination floor is determined to be the stoppable floor by the stoppable floor determination section.

Advantageous Effects of Invention

According to the invention, even during the travel of the car, the call corresponding to the destination floor is registered in the car. Accordingly, it is possible to improve the operation efficiency of the elevator.

BRIEF DESCRIPTION OF DRAWINGS

FIG. 1 is a block diagram of a control system of an elevator to which an elevator control system in Embodiment 1 of the invention is applied.

FIG. 2 is a hardware configuration diagram of each of a car control panel, a control device, and a group management device in the elevator control system in Embodiment 1 of the invention.

2

FIG. 3 is a flowchart for explaining the operation of the elevator control system in Embodiment 1 of the invention.

FIG. 4 is a flowchart for explaining the operation of the elevator control system in Embodiment 2 of the invention.

5 FIG. 5 is a flowchart for explaining the operation of the elevator control system in Embodiment 3 of the invention.

FIG. 6 is a flowchart for explaining the operation of the elevator control system in Embodiment 4 of the invention.

10 FIG. 7 is a flowchart for explaining the operation of the elevator control system in Embodiment 5 of the invention.

FIG. 8 is a flowchart for explaining the operation of the elevator control system in Embodiment 6 of the invention.

15 FIG. 9 is a flowchart for explaining the operation of the elevator control system in Embodiment 7 of the invention.

DESCRIPTION OF EMBODIMENTS

Embodiments of the invention will be described according to the accompanying drawings. Note that, in each drawing, the same or corresponding parts are designated by the same reference numerals. Redundant description of the parts will be appropriately simplified or omitted.

Embodiment 1

FIG. 1 is a block diagram of a control system of an elevator to which an elevator control system in Embodiment 1 of the invention is applied.

In FIG. 1, a hoistway that is not shown passes through 20 individual floors of a building. A plurality of cars that are not shown are provided in the hoistway. Each car moves up and down vertically in the hoistway.

The elevator control system includes a plurality of car control panels 1, a plurality of notification devices 2, a 25 plurality of control devices 3, and a group management device 4. Note that FIG. 1 shows one car control panel 1, one notification device 2, and one control device 3. Each car control panel 1 is provided in each car. Each notification device 2 is provided in each hall. Each control device 3 is 30 provided so as to correspond to each car. The group management device 4 is connected to each car control panel 1.

Each car control panel 1 includes a voice input section 1a, a voice recognition section 1b, a destination floor determination section 1c, a stoppable floor determination section 1d, a call registration section 1e, a response time estimation section 1f, and a notification section 1g.

45 The voice input section 1a receives an input of a voice uttered in a car during travel of the car. The voice recognition section 1b recognizes a floor based on the voice input to the voice input section 1a. Specifically, the voice recognition section 1b recognizes the floor based on the result of comparison between information on the voice input to the voice input section 1a and pre-stored floor information.

The destination floor determination section 1c determines 50 a destination floor based on the floor recognized by the voice recognition section 1b. The stoppable floor determination section 1d determines whether or not the destination floor determined by the destination floor determination section 1c is a stoppable floor during the travel of the car. Specifically, 55 the stoppable floor determination section 1d determines whether or not the destination floor is the stoppable floor based on the travel state of the car acquired from the control device 3.

60 In the case where the destination floor is determined to be the stoppable floor by the stoppable floor determination section 1d, the call registration section 1e registers a call corresponding to the destination floor in the car during the

travel of the car. At this point, the control device 3 causes the car to travel based on the call registered by the call registration section 1e.

In the case where the destination floor is not determined to be the stoppable floor by the stoppable floor determination section 1d, the response time estimation section 1f estimates a first response time until the travel state of the car is changed and the car arrives at the destination floor. At this point, the call registration section 1e registers the call determined based on the first response time estimated by the response time estimation section 1f in the car. Each of the notification section 1g and the notification device 2 provides a notification of information corresponding to the call determined based on the first response time estimated by the response time estimation section 1f.

Next, examples of the car control panel 1, the control device 3, and the group management device 4 will be described by using FIG. 2.

FIG. 2 is a hardware configuration diagram of each of the car control panel, the control device, and the group management device in the elevator control system in Embodiment 1 of the invention.

The car control panel 1 includes a first processing circuit 5a. The first processing circuitry 5a includes at least one first processor 6a and at least one first memory 7a. Each of the operations of the voice recognition section 1b, the destination floor determination section 1c, the stoppable floor determination section 1d, the call registration section 1e, and the response time estimation section 1f is implemented by execution of a program stored in at least one first memory 7a by at least one first processor 6a.

The control device 3 includes a second processing circuitry 5b. The second processing circuitry 5b includes at least one second processor 6b and at least one second memory 7b. The operation of the control device 3 is implemented by execution of a program stored in at least one second memory 7b by at least one second processor 6b.

The group management device 4 includes a third processing circuitry 5c. The third processing circuitry 5c includes at least one third processor 6c and at least one third memory 7c. The operation of the group management device 4 is implemented by execution of a program stored in at least one third memory 7c by at least one third processor 6c.

Next, the operation of the control system will be described by using FIG. 3.

FIG. 3 is a flowchart for explaining the operation of the elevator control system in Embodiment 1 of the invention.

In Step S1, it is determined whether or not the voice input section 1a receives the voice during the travel of the car.

In the case where the voice input section 1a does not receive the voice in Step S1, Step S1 is repeated. In the case where the voice input section 1a receives the voice in Step S1, the flow proceeds to Step S2.

In Step S2, it is determined whether or not the voice recognition section 1b recognizes the floor based on the voice input to the voice input section 1a. In the case where the voice recognition section 1b does not recognize the floor in Step S2, the operation is ended. In the case where the voice recognition section 1b recognizes the floor in Step S2, the flow proceeds to Step S3.

In Step S3, the destination floor determination section 1c determines whether or not the floor recognized by the voice recognition section 1b is the destination floor. In the case where the floor recognized by the voice recognition section 1b is not the destination floor in Step S3, the operation is

ended. In the case where the floor recognized by the voice recognition section 1b is the destination floor in Step S3, the flow proceeds to Step S4.

In Step S4, the stoppable floor determination section 1d determines whether or not the destination floor determined by the destination floor determination section 1c is the stoppable floor. For example, the stoppable floor determination section 1d determines whether or not the destination floor is the stoppable floor before the passage of the car based on the travel state of the car acquired from the control device 3. In the case where the destination floor determined by the destination floor determination section 1c is not the stoppable floor in Step S4, the operation is ended. In the case where the destination floor determined by the destination floor determination section 1c is the stoppable floor in Step S4, the flow proceeds to Step S5.

In Step S5, the call registration section 1e registers the call corresponding to the destination floor in the car. Thereafter, the operation is ended.

According to Embodiment 1 described above, even during the travel of the car, the call corresponding to the destination floor is registered in the car. Accordingly, it is possible to improve operation efficiency of the elevator.

Embodiment 2

FIG. 4 is a flowchart for explaining the operation of the elevator control system in Embodiment 2 of the invention. Note that parts identical or equivalent to those in Embodiment 1 are designated by the same reference numerals. Description of the parts will be omitted.

In Embodiment 1, in the case where the destination floor determined by the destination floor determination section 1c is not the stoppable floor in Step S4, the operation is ended. In contrast to this, in Embodiment 2, in the case where the destination floor determined by the destination floor determination section 1c is not the stoppable floor in Step S4, the flow proceeds to Step S6.

In Step S6, the call registration section 1e registers the call corresponding to the destination floor in the car after the car responds to all the calls registered in the car. Thereafter, the operation is ended. As a result, the car turns around and starts its travel. During the operation, the destination floor is a floor through which the car passes.

According to Embodiment 2 described above, in the case where the destination floor is not the stoppable floor, the call corresponding to the destination floor is registered in the car after the car responds to all the calls registered in the car. Accordingly, even in the case where the voice input by a user is late, it is possible to cause the car to arrive at the destination floor input by voice. As a result, it is possible to allow the user of which the voice input is late to go to a desired floor.

Embodiment 3

FIG. 5 is a flowchart for explaining the operation of the elevator control system in Embodiment 3 of the invention. Note that parts identical or equivalent to those in Embodiment 2 are designated by the same reference numerals. Description of the parts will be omitted.

In Embodiment 2, after Step S6, the operation is ended. In contrast to this, in Embodiment 3, after Step S6, the flow proceeds to Step S7.

In Step S7, in the case where a new hall call in the moving direction of the car is registered, the group management

5

device 4 assigns the new hall call to a car other this car. Thereafter, the operation is ended.

According to Embodiment 3 described above, in the case where the new hall call in the moving direction of the car is registered, the new hall call is assigned to a car other than this car. Accordingly, it is possible to prevent a time until the car turns around and responds to the destination floor from being prolonged due to the occurrence of the new hall call. As a result, it is possible to allow the user of which the voice input is late to go to the desired floor smoothly.

Embodiment 4

FIG. 6 is a flowchart for explaining the operation of the elevator control system in Embodiment 4 of the invention. Note that parts identical or equivalent to those in Embodiment 3 are designated by the same reference numerals. Description of the parts will be omitted.

In Embodiment 3, after Step S7, the operation is ended. In contrast to this, in Embodiment 4, after Step S7, the flow proceeds to Step S8.

In Step S8, in the case where the car responds to the last call of all the calls registered in the car, the notification device 2 provides a notification that the traveling direction of the car is reversed at the floor corresponding to the last call. For example, in the case where the notification device 2 is a hall lantern, the notification device 2 reverses display of a direction lamp. For example, in the case where the notification device 2 is a speaker, the notification device 2 outputs information that the traveling direction of the car is reversed by voice.

According to Embodiment 4 described above, the notification device 2 provides the notification that the traveling direction of the car is reversed in the case where the car responds to the last call. Accordingly, it is possible to prevent the user in the hall of the floor corresponding to the last car call from getting on the car by mistake.

Embodiment 5

FIG. 7 is a flowchart for explaining the operation of the elevator control system in Embodiment 5 of the invention. Note that parts identical or equivalent to those in Embodiment 4 are designated by the same reference numerals. Description of the parts will be omitted.

In Embodiment 4, in the case where the destination floor determined by the destination floor determination section 1c is not the stoppable floor in Step S4, the flow proceeds to Step S6. In contrast to this, in Embodiment 5, in the case where the destination floor determined by the destination floor determination section 1c is not the stoppable floor in Step S4, the flow proceeds to Step S11.

In Step S11, the response time estimation section 1f estimates a first response time until the car arrives at the destination floor after the car responds to all the calls registered in the car. At this point, the group management device 4 estimates a second response time until the user arrives at the destination floor in the case where the user gets off the car at the nearest floor at which the car can stop and transfers to another car.

The response time estimation section 1f determines whether or not the first response time is longer than the second response time. In the case where the first response time is shorter than the second response time, the flow proceeds to Step S6. In the case where the first response time is longer than the second response time, the flow proceeds to Step S12.

6

In Step S12, the call registration section 1e registers the call for the nearest floor at which the car can stop in the car. Thereafter, the operation is ended.

According to Embodiment 5 described above, in the case where the first response time is longer than the second response time, the call for the nearest floor at which the car can stop is registered in the car. Accordingly, it is possible to allow the user of which the voice input is late to go to the desired floor more quickly.

10 Embodiment 6

FIG. 8 is a flowchart for explaining the operation of the elevator control system in Embodiment 6 of the invention. Note that parts identical or equivalent to those in Embodiment 5 are designated by the same reference numerals. Description of the parts will be omitted.

In Embodiment 5, after Step S12, the operation is ended. In contrast to this, in Embodiment 6, after Step S12, the flow proceeds to Step S13.

In Step S13, the group management device 4 registers the call corresponding to the nearest floor at which the car can stop in another car. Thereafter, the flow proceeds to Step S14. In Step S14, the group management device 4 assigns the call corresponding to the destination floor to the other car. Thereafter, the operation is ended.

According to Embodiment 6 described above, in the case where the first response time is longer than the second response time, the call corresponding to the nearest floor is registered in the other car. Thereafter, the call corresponding to the destination floor is registered in the other car. Accordingly, it is possible to allow the user of which the voice input is late to go to the desired floor more quickly and more reliably.

35 Embodiment 7

FIG. 9 is a flowchart for explaining the operation of the elevator control system in Embodiment 7 of the invention. Note that parts identical or equivalent to those in Embodiment 6 are designated by the same reference numerals. Description of the parts will be omitted.

In Embodiment 6, after Step S11, the flow proceeds to Step S12. In contrast to this, in Embodiment 7, after Step S11, the flow proceeds to Step S21.

In Step S21, the notification section 1g notifies the user who desires to go to the destination floor of information for urging the user to get off at the nearest floor at which the car can stop and transfer to another car. For example, the notification section 1g provides the notification of the information by display or by voice. Thereafter, the flow proceeds to Step S12.

According to Embodiment 7 described above, the notification section 1g provides the notification of the information for urging the user to get off at the nearest floor at which the car can stop and transfer to another car. Accordingly, it is possible to urge the user who desires to go to the destination floor to transfer to another car more reliably.

INDUSTRIAL APPLICABILITY

60 Thus, the elevator control system according to the invention can be used in the system that improves the operation efficiency of the elevator.

The invention claimed is:

1. An elevator control system comprising:
 a processor to execute a program; and
 a memory to store the program which, executed by the
 processor, performs processes of,
 recognizing a floor based on voice information from in a
 car of an elevator during travel of the car,
 determining a destination floor based on the floor recog-
 nized,
 determining whether or not the destination floor deter-
 mined during the travel of the car is a stoppable floor
 in a travel direction, and
 registering a call corresponding to the destination floor in
 the car during the travel of the car in a case where the
 destination floor is determined to be the stoppable floor,
 wherein the program, executed by the processor, performs
 processes of,
 in a case where the destination floor is not determined to
 be the stoppable floor, registering the call correspond-
 ing to the destination floor in the car after the car
 responds to all calls registered in the car.
2. The elevator control system according to claim 1,
 further comprising
 a group management device configured to assign, in a
 case where a new hall call in a moving direction of the
 car is registered after the call corresponding to the
 destination floor is registered in the car after the car
 responds to all the calls registered in the car, the new
 hall call to a car other than this car.
3. The elevator control system according to claim 2,
 further comprising:
 a notification device configured to provide, in a case
 where the car responds to a last call of all the calls
 registered in the car, a notification that a traveling
 direction of the car is reversed in a hall of a floor
 corresponding to the last call.
4. The elevator control system according to claim 2
 wherein the program, executed by the processor, performs
 processes of estimating a first response time until the
 car arrives at the destination floor in a case where the
 call corresponding to the destination floor is registered
 in the car after the car responds to all the calls regis-
 tered in the car and in a case where the first response
 time estimated is longer than a second response time
 until a user arrives at the destination floor when the user
 gets of the car at a nearest floor at which the car can
 stop and transfers to another car, the call registration
 section registers a call for the nearest floor at which the
 car can stop in the car.

5. The elevator control system according to claim 4,
 wherein in the case where the first response time estimated
 is longer than the second response time until the user arrives
 at the destination floor when the user gets off the car at the
 nearest floor at which the car can stop and transfers to
 another car, the group management device registers the call
 for the nearest floor and a call for the destination floor in the
 other car.
6. The elevator control system according to claim 5,
 wherein the program, executed by the processor, performs
 processes of notifying, in the case where the first
 response time estimated is longer than the second
 response time until the user arrives at the destination
 floor when the user gets off the car at the nearest floor
 at which the car can stop and transfers to another car,
 the user who desires to go to the destination floor of
 information for urging the user to get off at the nearest
 floor at which the car can stop and transfer to the other
 car.
7. An elevator control system comprising:
 processing circuitry configured to
 recognize a floor based on voice information from
 within a car of an elevator during travel of the car
 determine a destination floor based on the floor recog-
 nized,
 determine whether or not the destination floor deter-
 mined during the travel of the car is an upcoming
 floor in a travel direction, and
 register a call corresponding to the destination floor in
 the car during the travel of the car in a case in which
 the destination floor is determined to be the upcom-
 ing floor,
 wherein the processing circuitry is further configured to
 in a case in which the destination floor is not determined
 to be the upcoming floor, register the call correspond-
 ing to the destination floor in the car after the car
 responds to all calls registered in the car.
8. An elevator control system comprising:
 processor to execute a program;
 a memory to store the program which, executed by the
 processor, performs processes of,
 recognizing a floor based on voice information from in a
 car of an elevator during travel of the car,
 determining a destination floor based on the floor recog-
 nized,
 determining whether or not the destination floor deter-
 mined during the travel of the car is a stoppable floor
 in a travel direction, and
 registering a call corresponding to the destination floor in
 the car during the travel of the car in a case where the
 destination floor is determined to be the stoppable floor,
 wherein the program, executed by the processor, performs
 processes of,
 in a case where the destination floor is not determined to
 be the stoppable floor, registering the call correspond-
 ing to the destination floor in the car after the car
 responds to all calls registered in the car; and
 a group management device configured to assign, in a
 case where a new hall call in a moving direction of the
 car is registered after the call corresponding to the
 destination floor is registered in the car after the car
 responds to all the calls registered in the car, the new
 hall call to a car other than this car.
9. The elevator control system according to claim 8,
 further comprising:
 a notification device configured to provide, in a case
 where the car responds to a last call of all the calls

registered in the car, a notification that a traveling direction of the car is reversed in a hall of a floor corresponding to the last call.

- 10.** The elevator control system according to claim **8**, wherein the program, executed by the processor, performs processes of estimating a first response time until the car arrives at the destination floor in a case where the call corresponding to the destination floor is registered in the car after the car responds to all the calls registered in the car and in a case where the first response time estimated is longer than a second response time until a user arrives at the destination floor when the user gets off the car at a nearest floor at which the car can stop and transfers to another car, the call registration section registers a call for the nearest floor at which the car can stop in the car.
- 11.** The elevator control system according to claim **10**, wherein in the case where the first response time estimated is longer than the second response time until the

5

10

15

user arrives at the destination floor when the user gets off the car at the nearest floor at which the car can stop and transfers to another car, the group management device registers the call for the nearest floor and a call for the destination floor in the other car.

- 12.** The elevator control system according to claim **11**, wherein the program, executed by the processor, performs processes of notifying, in the case where the first response time estimated is longer than the second response time until the user arrives at the destination floor when the user gets off the car at the nearest floor at which the car can stop and transfers to another car, the user who desires to go to the destination floor of information for urging the user to get off at the nearest floor at which the car can stop and transfer to the other car.
